DRAWBRIDGE CIRCUIT CONTROLLER AND
OPERATING MEANS THEREFOR

Thomas George Stiles, Arlington, N. J.

Application November 9, 1934, Serial No. 752,262

10 Claims. (Cl. 14—35)

The invention relates to improvements in drawbridge circuit controllers and operating means therefor; the circuit controllers of the present invention being of the same general type as that disclosed in my prior Patent No. 1,030,622, dated June 25, 1912.

One of the main objects of the invention is to combine circuit controllers of this type with a bridge locking mechanism whereby the latter, when operated to either lock or unlock the bridge, will thereby automatically operate the controllers to either close or open the circuits, as may be desired.

Other objects and advantages of the invention will be referred to in the detailed description of the invention which follows.

The invention is illustrated in the accompanying drawings, in which I have shown a traction track circuit controller and an indicator circuit controller both combined with a bridge locking mechanism for operation thereby.

In these drawings—

Fig. 1 is a plan of the bridge locking mechanism and circuit controllers embodying my invention, with the parts shown in closed or operative positions as when the bridge is closed.

Fig. 2 is a similar view with the parts in open or inoperative positions as when the bridge is open or ready to be opened.

Fig. 3 is a vertical section of the controller unit with the traction track circuit controller in closed position, as in Fig. 1.

Fig. 4 is a similar view of the controller unit with the traction track circuit controller in open position as in Fig. 2.

Fig. 5 is a view similar to Fig. 3 on an enlarged scale.

Fig. 6 is a view of the bridge abutment member of the traction track circuit controller shown in Figs. 3 and 4, on the same enlarged scale as that of Fig. 5, and showing in full and dotted lines the two positions of the movable parts.

Fig. 7 is a cross section on the line 7—7 of Fig. 5.

Fig. 8 is a plan view similar to Fig. 1, but on an enlarged scale, with some of the parts broken away and in section for the clearer illustration of the details of construction.

Similar reference characters designate like parts in the several figures of the drawings.

In these drawings, 1 indicates the casing of the draw-bridge abutment member of the traction track circuit controller, which casing is in the form of a rectangular open top box having its forward end provided with a perforation for the projection therethrough of the sliding contact rod 10 of the controller. This casing may be fixed to the abutment member of the bridge, indicated generally at A, in any suitable manner, as by means of bolts or screws (not shown).

passing through openings 3—3 formed in the bottom of the casing and in transverse reinforcing strips 4—4 attached to the under side of the casing at such points. A plurality of these openings 3—3, arranged lengthwise of the casing as shown, are provided to permit of the adjustment of the casing with its supported parts lengthwise of the abutment and relatively to the casing on the bridge carrying the contact element with which the rod 10 cooperates.

Slidably mounted on the casing 1, preferably by means of rollers 6 attached to the sides of the latter near its top, is a cover 7. This cover has depending flanges 8 at the sides and rear end thereof which extend down over the outside 15 of the upper edges of the casing to keep out rain, snow, etc. Said cover is connected with the sliding contact rod 10 for movement therewith, by means to be presently described, and is of a length sufficiently greater than the casing 1 as 20 to effect a telescoping connection with the adjacent end of the bridge member of the controller when the electrical contacts of the traction track circuit controller are engaged, as shown in Figs. 3 and 5. When the electrical contacts of 25 this controller are disengaged, as in Fig. 4, the rear end of the cover will extend a substantial distance rearwardly of the end wall of the casing.

The cover 7 adjacent its rear end and outside 30 of the casing 1 is provided with a rigidly connected depending bracket arm 15 in which is fixedly mounted a horizontally arranged rod 16, which latter at its forward end slidably extends through an opening in the rear wall of the casing 1 and 35 is connected through the medium of an insulating block 17 (see Fig. 6) with the rear end of the sliding contact rod 10 at a point within said casing. In this way the cover 7 and contact rod 10 are united for simultaneous movement 40 upon the shifting of said rod to and from its position of electrical contact with the cooperating element of the controller. The rod 16 at its rear end is connected with the bridge locking mechanism whereby the contact rod and attached 45 cover will be operated by said mechanism in a manner to be presently described.

The contact rod 10, which is of the same general character as the contact rod described in my prior patent aforesaid, projects at its forward end, as 50 hereinbefore referred to, through a perforation in the end wall member of the casing in which it is slidably supported. This end wall member, indicated at 20, is formed of insulating material and is removably secured in position at the end 55 of the casing by suitable fastening means, such as the retaining brackets 21 attached to the side walls of the casing and having inwardly turned flanges engaging the member 20 within peripheral recesses therein as shown. Secured to the 60

rear side of the wall member 20 is a series of spring finger contacts 23 which engage the angular edges of the rod 10, which latter as here shown is hexagonal in cross section (see Fig. 7). 5 Preferably the spring contacts are secured to a suitable base 24 by means of bolts 25 engaging the member 20 through openings therein as shown. Also carried by said base 24 are the terminals, such as 26, for the attachment of the circuit wires, such as 27.

The complementary member of the circuit controller, carried on the draw-bridge, indicated generally at B, comprises a generally rectangular casing 30 corresponding substantially with the 15 casing I on the draw-bridge abutment just described and having openings 31 in its bottom wall to receive fastening screws (not shown) for securing the same to the bridge member.

Secured in the front end of the casing 30 by 20 retaining brackets 33, similar to the brackets 21 hereinbefore described, is a wall member 34 which is preferably made of insulating material and provided with a perforation to receive therethrough the end of the contact rod 10 when the 25 latter is advanced to close the traction circuit upon the closing of the bridge. Mounted on the rear face of the member 34 is a series of spring contacts 36 constructed, arranged and mounted like the spring contacts 23 in the casing I, these 30 contacts being secured to a base 37 by means of bolts 38 engaging the member 34 through openings therein and which base carries terminals 39 for the attachment of circuit wires 40 which form continuations of the leads or wires 27 connected 35 to the contacts 23 carried by the casing I.

As a means to increase the contact surface of the socket elements of this controller, as composed of the two sets of spring fingers 23 and 36, with the contact rod 10, whereby a quick pick-up of 40 current is assured when the rod 10 is brought into circuit closing position, I supplement each of said sets of spring fingers 23 and 36 with a second set of fingers, indicated at 23' and 36' respectively, which are positioned immediately 45 below the fingers of the first sets and secured in position on the base members by the same fastening bolts which secure the outer fingers, as clearly shown in Figs. 5 and 6; these supplemental spring fingers being of less length than the outer ones 50 and adapted to engage with the contact rod at the rear of the latter as shown.

The circuit in which the described controller is employed is, as stated, a traction track circuit, the circuit wires connecting with the electrical contact elements of the controller being adapted to have electrical connection in usual manner with track sections or rails, such as indicated at 50 and 51, mounted respectively on the draw-bridge and draw-bridge abutment.

60 In connection with the described traction circuit controller, I also employ for cooperation therewith a separate controller for the usual indicator circuit. This latter controller is here shown as mounted in the rear end of the draw-bridge casing 30, which is made sufficiently long for such purpose, and it comprises two spring contact devices, indicated generally at 60 and 60', located respectively in the circuits of the usual so-called "open" and "closed" bridge signals to be controlled 65 and a reciprocatory contact rod 65 adapted for alternative engagement and disengagement with the respective contact devices to thereby make and break the circuits through them to the respective indicators. These indicator contacts, as 70 here shown, each comprise a pair of oppositely

disposed contact springs through which the circuit is made and broken by the engagement and disengagement respectively of the adjacent ends of the contact rod 65. These contact springs are mounted on cross panels of insulating material, 5 the panel carrying the device 60 being indicated at 61 and that carrying the device 60' being indicated at 61' and both being secured at their ends to the opposite side walls of the casing by suitable angle pieces 62. Preferably the spring contacts 10 are secured to the panels by screws or bolts 70 which are of sufficient length to constitute binding posts for the attachment of the usual circuit wires, such as indicated at 71.

The contact rod 65 of this indicator circuit controller is mounted about centrally thereof in a bracket arm 66 fixedly attached to a horizontally arranged carrier rod 67, which latter is slidably mounted in openings in the panels 61 and 61' with its rear end extending outwardly through the 20 rear end of the casing for connection with certain operating means to be presently described. A bushing 68 of insulating material in the opening of the arm 66 in which the contact rod 65 is supported serves to insulate the latter from said arm, 25 as shown in Figs. 5 and 8.

The draw-bridge locking means as here shown comprises a locking rod mounted on the draw-bridge abutment and a socket member mounted on the draw-bridge to receive one end of said 30 locking rod. The locking rod, indicated at 80, is mounted for horizontal sliding movement within openings formed in raised ribs 81—81 on a base member or casting 82 which is firmly secured to the bridge abutment by a suitable fastening means, such as screws or bolt (not shown), and the socket, indicated at 84, to receive the end of said rod is formed in a raised rib 85 mounted on a second base member or casting 86 which is firmly secured on the draw- 40 bridge by a suitable fastening means, such as screws or bolts (not shown). Said locking rod is operatively connected with the slideable contact rod 10 of the traction circuit controller through the medium of a rod 87 which is rigidly 45 attached at one end to the locking rod and at its opposite end with the rear end of the rod 16 at a point outside of the casing I, this latter rod 16 being connected at its front end with the contact rod 10 at a point within the casing as 50 hereinbefore described. With this arrangement of parts, when the locking rod on the bridge abutment is advanced into locking engagement with the socket member on the bridge, following the closing of the latter, the contact rod 10 is 55 thereby moved into circuit closing contact with the cooperating contact device on the bridge, as shown in Fig. 1. Subsequently, upon the withdrawal of the locking rod from locking engagement with its cooperating socket member to permit opening of the bridge, said contact rod will 60 also be thereby withdrawn from engagement with its cooperating contact device and so break the circuit, as shown in Fig. 2.

The locking rod may be operated for movement to and from its locking position by any suitable means. As shown in Fig. 1, it has a pin and slot connection with the end of a rocker arm 88 fixed to an oscillating shaft 89, which latter may be operated by any usual or suitable mechanism.

As a means to also effect operation of the indicator circuit controller in cooperation with the traction circuit controller upon the locking and unlocking of the bridge, I slidably mount a rod 75

90 within openings in raised ribs 91—91 on the base member 86, which rod is arranged in alignment with the locking rod 80 and is yieldingly held with its free end in engagement with the 5 adjacent end of the locking rod by means of a coiled expansion spring 92 located thereon with one end engaging a stationary block 93 and its opposite end engaging a collar 94 on the rod. A rigid connection between this rod 90 and the 10 carrier rod 67 of the indicator contact rod 65 is effected by a cross rod 95 rigidly connected at its opposite ends with said rods 90 and 67 respectively adjacent their rear ends as shown. With this combination and arrangement of parts, 15 when the operator withdraws the locking rod 80 from locking engagement with its cooperating socket member, preliminary to the opening of the draw-bridge, the connected contact rod 10 of the traction circuit controller is at the same 20 time positively withdrawn from its cooperating contact device to thereby break such circuit. At the same time, the rod 90, under the influence of the spring 92, is caused to follow up the engaging rod 80, from the position shown in Figs. 1 25 and 8 to that shown in Fig. 2, and thereby move the contact rod 65 of the indicator circuit controller from engagement with the cooperating contact device 60 of the "open" indicator circuit to engagement with the co-operating contact 30 device 60' of the "closed" indicator. Thereafter, upon the closing of the bridge, when the locking rod 80 is moved to locking position, such movement will advance the contact rod 10 into engagement with its cooperating contact device 35 to close the traction track circuit and at the same time will engage with the rod 90 and move the same rearwardly against the pressure of the spring 92 to shift the contact rod 65 from engagement with the contact device 60' of the "closed" indicator and into engagement with the contact device 60 of the "open" indicator to effect 40 operation of the latter.

The indicator instrument proper, which indicates "closed" when the bridge is closed and "open" when the bridge is open, is ordinarily located in the so-called "operating room" of the operating tower, and by combining the circuit controller of this with the circuit controller of the track circuit through a common operating means, such for example, as the bridge locking mechanism herein disclosed, it will be understood that the operation of the indicator in the operating room will show the operator there whether the main or track circuit controller is 45 functioning properly. If it is not, because for example of any of the mechanical connections being broken or otherwise out of order, such fact will be indicated to the operator because of the like failure of the indicator to function. In other words, the association of the indicator circuit controller with the main or track circuit controller for operation from a common control, will result in failure of the indicator to properly function in the event of the failure of the main 50 or track circuit controller to properly function and show the operator accordingly. In this way, possibility of damage resulting because of the lack of proper functioning of the track circuit controller is avoided.

The traction track circuit of the main controller herein described is adapted for a high current, such for example, as one of 220 amperes or higher and 10,000 volts. Because of such high current, when the plug element or contact rod 10 is advanced into engagement with the

group of springs 36 constituting the socket element to thereby make the circuit through them, flashing results with a consequent tendency to burn and damage the springs. To avoid this I insulate the front end of the contact rod, as indicated at 10'. By doing this and insulating the interior walls of the enclosing casing 30, as at 30', I am enabled to operate the controller dry, rather than in oil as heretofore, the advantages of which are obvious.

As herein shown and described, the plug unit of the traction circuit controller, comprising the casing 1 and supported parts, is mounted on the bridge abutment, while the socket unit, comprising the casing 30 and supported parts, together with the indicator circuit controller unit, is mounted on the bridge. It will be understood however that the mounting of these parts, together with the associated bridge locking mechanism, may be reversed as to the bridge and bridge 20 abutment without in any way departing from the spirit of my invention.

What I claim is:

1. The combination with a draw-bridge and draw-bridge abutment, of a circuit controller comprising cooperating contact members mounted respectively on said draw-bridge and draw-bridge abutment and one being slidably mounted for movement to and from engagement with the other to make and break the circuit, a draw-bridge locking device comprising interlocking members also mounted on said draw-bridge and draw-bridge abutment respectively and one being slidably mounted for movement to and from locking engagement with the other, the slidable movement of said locking member being parallel with that of the slidable contact member, and an operative connection between said slidable member of the locking device and the slidable contact member of the circuit controller whereby, upon movement of the slidable locking member to and from its operative position of locking engagement with the cooperative locking member, the slidable contact member of the circuit controller will thereby be operated to engage and disengage with its cooperating contact member.

2. The combination with a draw-bridge and draw-bridge abutment, of circuit controller casings mounted on said draw-bridge and abutment, a circuit controller comprising cooperating contact members mounted respectively in said casings and one being slidable to and from engagement with the other to make and break the circuit, a cover slidably mounted on the casing containing the slidable contact member and connected with the latter for movement in unison therewith whereby it will telescope with the second casing when the contacts are brought into engagement, a draw-bridge locking device comprising interlocking members also mounted on said draw-bridge and draw-bridge abutment respectively and one being slidably mounted for movement to and from locking engagement with the other, the slidable movement of said locking member being parallel with that of the slidable contact member, and an operative connection between said slidable member of the locking device and the slidable contact member of the circuit controller whereby, upon movement of the slidable locking member to and from its operative position of locking engagement with the cooperative locking member, the slidable contact member of the circuit controller will thereby be operated to engage and disengage with its cooperating contact member.

operated to engage and disengage with its cooperating contact member.

3. The combination with a draw-bridge and draw-bridge abutment, of an indicator circuit controller comprising cooperating contact members one of which is movable to and from engagement with the other to make and break the circuit, a draw-bridge locking device comprising interlocking members mounted on the draw-bridge and draw-bridge abutment respectively and one being slidably mounted for movement to and from locking engagement with the other, an actuating rod slidably mounted for reciprocatory movement, means operatively connecting the movable controller contact member with said actuating rod to be moved by the latter to and from engagement with its cooperating contact member, said actuating rod being engaged and moved in one direction by the slidable locking member when moved to locking position, and means for automatically moving said actuating rod in the opposite direction upon the movement of the slidable locking member to unlocked position, the said actuating rod and slidable locking member being mounted, one on the draw-bridge and the other on the draw-bridge abutment, for independent bodily movement.

4. The combination with a draw-bridge and draw-bridge abutment, of an indicator circuit controller mounted on the draw-bridge and comprising two contact devices, including a pair of insulated contact springs, and a reciprocatable contact rod adapted for alternative engagement and disengagement at its opposite ends with said contact springs, a draw-bridge locking device comprising interlocking members mounted on the draw-bridge and draw-bridge abutment respectively and one being slidably mounted for movement to and from locking engagement with the other, an actuating rod slidably mounted for reciprocatory movement, means operatively connecting the reciprocatable controller contact rod with said actuating rod to be moved by the latter to and from engagement with the cooperating contact devices, said actuating rod being engaged and moved in one direction by the slidable locking member when moved to locking position, and means for automatically moving said actuating rod in the opposite direction upon the movement of the slidable locking member to interlocking position.

5. The combination of a draw-bridge and draw-bridge abutment with a traction track circuit controller, an indicator and indicator circuit controller serving to indicate the functioning of said track circuit controller each of said controllers comprising cooperating contact members, one of said contact members of each controller being slidably mounted for movement to and from engagement with the other to make and break their respective circuits, one contact member of said circuit controller being mounted on said draw-bridge and one being mounted on said abutment; a draw-bridge locking device comprising interlocking members mounted on said draw-bridge and draw-bridge abutment, respectively, and one being slidably mounted for movement to and from locking engagement with the other, and connecting means between said slidable interlocking member and said slidable contact members, whereby, upon movement of the slidable locking member to and from its operative position of locking engagement with its co-

operative locking member, the slidable contact members of said controllers will thereby be operated to engage and disengage with their cooperating contact members.

6. The combination of a draw-bridge and draw-bridge abutment with a draw-bridge locking device, a traction track circuit controller and an indicator and indicator circuit controller serving to indicate the functioning of said track circuit controller, each of said controllers comprising cooperating contact members, one of said contact members of each controller being mounted for movement to and from engagement with the other to make and break their respective circuits; said draw-bridge locking device comprising a locking rod slideable to and from engagement with a socket; a second slideable rod aligned with said locking rod and actuated thereby, said locking rod being operatively connected to one of said movable contact members and said second slideable rod being operatively connected to the other of said members whereby, upon operation of said locking rod, said traction track circuit controller and said indicator controller are simultaneously operated.

7. The combination of claim 1 wherein the slideable contact member of said circuit controller comprises a contact rod adapted to slide into and out of engagement with cooperating spring contact fingers, the operative end of said contact rod being provided with insulation to diminish sparking.

8. The combination of claim 3 wherein the movable contact member of said indicator circuit controller comprises a double ended contact rod, the respective ends of which are adapted to slide into and out of engagement with two sets of cooperating spring contact fingers, thereby closing circuits to indicate the position of said draw-bridge locking device.

9. The combination of claim 5 wherein the movable contact members of said traction track circuit controller and said indicator circuit controller comprise contact rods adapted to slide into and out of engagement with cooperating spring contact fingers, the operative end of said contact rod of said track circuit controller being insulated in order to diminish sparking.

10. The combination with a draw-bridge and draw-bridge abutment, of a signal circuit controller comprising cooperating contact members, slidably mounted for movement to and from engagement with another member to operate the signal circuit, a draw-bridge locking device comprising interlocking members mounted on the draw-bridge and draw-bridge abutment, respectively, adapted to be moved to and from interlocking engagement, at least one of said interlocking members being slidably mounted, the sliding movement of said interlocking member being parallel to that of said slidable contact member, and an operative connection between said slidable member of said locking device and the slidable member of said signal circuit, whereby, upon movement of the slidable interlocking member to and from its operative position of interlocking engagement with the cooperative locking member, the slidable contact member of the signal circuit will thereby be operated to engage and disengage with its cooperating contact member, thereby indicating the position of said interlocking member.

THOMAS GEORGE STILES.
